Application December 12, 1940, Serial No. 369,829

22 Claims. (Cl. 179—100.11)

1

The present invention relates broadly to recording and reproducing systems and more particularly to the recording of sound or other signals in the form of a timing modulated high frequency wave; that is, a high frequency wave modulated in phase or frequency, in accordance with the signal wave form, or a voltage derived therefrom.

In the present specification the term timing modulation will be used to designate either or both phase modulation and frequency modulation. Accordingly it is to be understood that when either of the terms "frequency modulation" or "phase modulation" is used the other is not excluded since it is a well known fact that either type of modulation may be used with the same result as the other by suitably altering the frequency characteristic of the modulating voltage of one with respect to that of the other.

The present invention has for one of its objects to provide a system of recording and reproducing which possesses substantially the same advantages as are obtained in frequency modulated radio transmissions, and in addition other advantages which are of particular interest and importance in the recording and reproducing art.

Thus, among the objects of the present invention is the provision of a phonographic system capable of wide dynamic range, increased length of playing time for any given size record, and greatly reduced incidental noise background.

In the usual methods of recording now prevalent, the requirement of recording accurately various wave forms having a wide frequency range and a large amplitude range, is so severe that ideal operation is by no means secured. For example, for high fidelity work, the vibration of the recording needle must have a smooth frequency characteristic over the entire range of audible frequencies; namely, a range of some 300 to 1, and in addition the reproducing pickup must have similarly excellent characteristics over this wide range. With equalizer systems, as in use at present, the desired over-all faithfulness of reproduction can only be approximated and then only with considerable loss in efficiency, both on recording and reproducing.

Again, in order to maintain a good ratio of "desired signal" to "surface noise," it has been necessary to reduce the dynamic range of musical recordings in order to prevent overloading the system during loud passages on the one hand, and on the other hand to assure that during

51 pianissimo passages the noise will not be too evident.

Another disadvantage of the systems now generally in use, is the necessity of making adjacent 5 grooves on a phonograph record sufficiently spaced to accommodate large amplitudes of vibration of the stylus (such as occur during loud passages) without cutting over into the adjacent groove. This limits the number of grooves 10 per inch, and correspondingly limits the playing time of a record.

In accordance with the present invention, all 15 of the above mentioned drawbacks of present day systems are avoided by recording not the original signal wave, but a super-audible frequency carrier wave of constant amplitude, whose frequency is varied about a mean frequency in accordance with the instantaneous potential of the signalling wave itself, or of a voltage derived 20 therefrom.

In the matter that follows, the term "frequency modulation" will be used for the sake of definiteness, however, it should be appreciated that the recording mechanism may be of the phase modulating type, and that the signalling wave may be altered in any desired manner by passage 25 through a suitable network before being impressed upon the modulating system.

Continuing on the assumption that a frequency 30 modulation is used, a system incorporating certain of the features of the invention might be as follows:

35 Audio signals to be reproduced may be first passed through any desired arrangements for pre-emphasizing certain frequencies (if this is desirable) or for expanding or compressing their dynamic range. The resulting energy which is herein called the modulating potential, is then used to modulate a source of superaudible frequency, which may have a mean frequency of 40 50,000 cycles, for example. The maximum modulation voltage might be arranged to cause the instantaneous frequency to swing as high as 80,000 cycles, or as low as 20,000 cycles. This constant 45 amplitude frequency modulated wave is then impressed upon a piezo-electric crystal, whose natural frequency is preferably above the highest frequency to be recorded, and the vibrations of this crystal are imparted to a suitable recorder which may comprise a very light cutting or embossing point. Various methods of cutting or embossing are contemplated by the present invention. For instance, in one such method, a record blank may be provided which has a prepared groove and the embossing may be per-

formed within the groove by a crystal-driven, rounded-point, embossing tool. In such an arrangement since the embossing is within the groove, the embossed track is out of harm's way. In still another arrangement contemplated by the present invention, a cutting or embossing tool is used which preferably vibrates up and down on the blank record thus producing a record of the type known as "hill and dale."

In such an arrangement the embossing may be performed within a previously prepared groove in which case the cutting or embossing tool is guided by the groove, or the embossing may be performed on the "land" of a record with a previously prepared spiral groove. In the latter case, the groove may be used in conjunction with a groove follower associated with the embossing tool to guide or feed the embossing tool along the "land" of the record.

One of the above noted advantages of the present invention becomes immediately apparent since the combination of "hill and dale" recording in a system wherein the amplitude of vibration is substantially constant, permits a great increase in the number of lines per inch. It has been found that a line density of the order of 500 lines to the inch is readily possible. This means that a twelve inch record would play for more than 15 minutes at 78 R. P. M. (revolutions per minute) without using as much as the outer 3 inches of radius. It may be noted in passing that with the particular frequency values given above as illustrative, the longest wave length that will be engraved on the record will occur when the instantaneous frequency has dropped to 20,000 cycles at the outer portion of the record, and this wave length will be about two and one-half thousandths of an inch, while the shortest wave length will result from an instantaneous frequency of 80,000 cycles, occurring in the inner portion of the record, and will be about one-third of a thousandth of an inch. Such minute wave lengths might not be feasible to record or reproduce with a system required to function over the wide percentage range of frequencies and amplitudes that is met in present day practice, but it is perfectly feasible where, as in the present invention, the percentage range of frequencies is so greatly reduced and the amplitude is substantially constant.

While a constant amplitude has been referred to above, what is meant in that no attempt is made to vary the amplitude. As a matter of fact even if the cutting stylus, or reproducing arrangement has an inherent tendency to operate more efficiently at one frequency than another, it will make little or no difference in the final result because in accordance with the invention the reproducing circuits, as will be seen hereinafter, include limiter devices for nullifying the effect of amplitude variations.

In reproducing from a record produced in accordance with the invention, a crystal pickup device may be used operating similarly to the recorder, and this pickup device will then pick up mechanical vibrations which it transforms into electrical energy in the form of a frequency-modulated, super-audible frequency voltage, whose amplitude is more or less constant. If the amplitude of this voltage varies considerably with frequency it may be passed, if desired, through corrective networks for restoring it to more nearly a constant value, but in any case, after sufficient amplification it will preferably be passed through a limiter stage for removing substantially all

amplitude modulation. Following the limiter there may be provided the usual type of frequency modulation discriminator-detector, or preferably, in view of the relatively low frequencies involved, the limiter may be followed by a detection system similar to that described in my co-pending United States patent application, Serial No. 354,982, filed August 31, 1940, now Patent No. 2,286,377, granted June 16, 1942.

The present invention also provides for producing a record of the type described, by a method of slow speed recording. One way in which this may be accomplished is to first make a record of the audio-frequency of the conventional type but with highest possible fidelity and then playing back this record at a slower speed. The reproduction from this playback or a voltage derived therefrom is then used to frequency modulate a wave the frequency of which is reduced from the desired carrier frequency in the same proportion as the above mentioned playback speed was reduced from the recording speed. The resulting frequency modulated wave is recorded on a record which is running at a speed which is reduced from the desired speed of reproduction in the same proportion as the above mentioned carrier was reduced from the desired carrier. In reproducing the last mentioned record, the record is run at the said desired speed of reproduction.

The present invention also provides an arrangement for recording frequency modulated signals picked up by a frequency modulation receiver.

Assuming that such a receiver is provided with a radio frequency amplifier, a converter including an oscillator, an intermediate frequency amplifier, a limiter, a discriminator-detector, an audio-frequency amplifier, and a loud speaker, then the output of either the intermediate frequency amplifier or the limiter is converted to a suitable intermediate frequency and passed through a frequency divider thereby reducing both mean frequency and frequency swing to proper values for recording. The energy may then be amplified and fed to the recorder mechanism and impressed upon a record as heretofore mentioned. If, as may happen, the intermediate frequency swing referred to above cannot be directly subdivided to the proper recording value, it may be necessary to use a frequency divider in combination with a frequency multiplier. It is obvious from a mathematical standpoint that by properly combining frequency conversion, frequency division, and frequency multiplication, substantially any combination of mean frequency and frequency swing may be obtained. Once the desired swing is obtained, additional converters may always be utilized to convert the energy to the proper mean frequency after which it is amplified and fed to the recorder.

Another feature of the present invention is the provision of means for reproducing records made in accordance with the invention through a frequency modulation receiver. In such a case, a suitable pickup is used for picking up the energy from the record as previously described and its voltage fed through an amplifier and then through a frequency multiplier and a converter in order that the energy may be converted to energy of a mean frequency and a frequency swing which correspond to the frequency and band width respectively of the intermediate frequency amplifier of the receiver. When such energy is obtained it may be fed into the input of the

receiver intermediate frequency amplifier from which it is passed through the limiter thence through the discriminator detector, thence through the audio-frequency amplifier and lastly impressed upon the loud speaker.

It is appreciated that the invention may be used in conjunction with a constant linear speed type of disc drive in order that the waves may be kept uniform throughout the portion of the disc used. Also, the spiral groove on the record may be used for guiding purposes only on both recording and playing back in which case the recording is put on the "land."

Among other objects of the invention are the provision of photo-electric pickup means arranged to respond to light reflected from the "land" of the record for reproduction of the recorded signals.

While the invention will be described in connection with disc records it is not intended to be limited thereto since other types of records may be used. In other words, it should be distinctly understood that the invention may be practiced equally well with other types of records which may include among others magnetic type records, photographic on film type records, records made by cutting through an opaque layer on film or by embossing on film, records which employ variable pressure on a conducting pickup in order to provide for varying contact resistance. Such a variable contact resistance may be provided also by the intermittent interruption of a circuit by virtue of the failure of the pickup needle to follow exactly a "hill and dale" record track. This would occur for instance when the pickup needle fails to dip into the "dale" portions of the record track but instead jumps from "hill" to "hill" of the track.

The novel features which are believed to be characteristic of the invention are set forth in particularity in the appended claims. The invention itself, however, as to both its organization and method of operation will best be understood by reference to the following description taken in connection with the drawing in which there have been indicated diagrammatically several organizations whereby the invention may be carried into effect.

In the drawing, Figure 1 is a diagrammatic representation of a circuit organization and recorder unit which may be used for producing records in accordance with the present invention; Figure 2 is a diagrammatic representation of a suitable circuit and pickup means which may be used for reproducing the recorded signals; Figure 3 illustrates in diagrammatic form a frequency modulation receiver with circuit arrangements for reproducing and making records in accordance with the present invention; Figures 4A and 4B diagrammatically represent an arrangement which may be used for reduced speed recording; Figure 5 is a section through a record perpendicular to a radius of the disc showing the "land" and a portion of the embossing tool; Figure 6 is a cross-section of the recording disc along a diameter thereof, the disc being of the type where the groove is used as a guide for the pickup device or embossing means; and, Figure 7 illustrates an arrangement using reflected light from the "land" of the record for reproducing the signals.

Referring more particularly to Figure 1 of the drawing, 16 is a motor for driving a turn table 13 through reduction gearing 15 and shaft or spindle 14. A record 12 is shown on the turn table with the spindle 14 passing through an

opening in the record suitably and arranged so as to prevent slippage. The record 12 is shown as being cut or embossed by tool 11 which is driven by a piezo-electric crystal 8. The tool is mounted on the crystal in any suitable manner. In this way, the motion of the crystal is transferred to the tool moving it up and down and thereby embossing or cutting the record track accordingly.

While a crystal has been shown as the driving means for the tool 11, it is to be understood that other types of drivers may be used such as an electro-magnetic driver. Crystal 8 is mounted between plates 9 and 10 and the driving voltage is impressed between the plates 9 and 10.

A modulating potential derived from the signal to be recorded is impressed across terminals 1 and 2 and thereby fed to a reactance tube circuit 3 which acts to frequency modulate the oscillations produced by oscillator 4 in accordance with the modulating potential. To obtain suitably large frequency variations, it is preferable to make the mean frequency generated by oscillator 4 higher than the mean frequency which is to be used for the actual operation of the embossing tool or cutter. Accordingly, the frequency modulated output of oscillator 4 is fed to a converter circuit 5 wherein the energy is converted to lower frequencies. The output of the converter 5 is preferably amplified in a suitable wide band amplifier 6 which may take the form of the amplifier illustrated in Figure 4 of United States Patent No. 1,925,340. The output of amplifier 6 is then impressed between previously mentioned plates on electrodes 9 and 10 of crystal 8. Thus, the crystal 8 moves in accordance with the output voltage of amplifier 6.

To play back the record 12 after the desired signals are recorded thereon, a system like that shown in Figure 2 may be used. In Figure 2, as in Figure 1, a turn table 13 is driven by a motor through gear reduction means 15 and shaft or spindle 14. The record 12 is placed on the turn table 13 with its central opening registering with spindle 14 in the usual manner. As the record is rotated the pickup 17 travels along the spiral groove and the vibrations imparted to pickup 17 by the waves on the record are transformed into electrical energy. If a crystal pickup is used, the follower or needle acts to variably deform the crystal in accordance with the recorded matter.

The electrical energy is preferably amplified in an amplifier 18 and then fed to a discriminator-detector 19 of any suitable type from which the audio signals are derived. After amplification in an amplifier 20 the audio signals are fed to a loud speaker 21 in the usual manner.

If it is desired to make records of the type described herein, from broadcasts received by a frequency modulation receiver, or if it is desired to play back records produced in accordance with the present invention through a frequency modulation receiver designed for radio reception, an arrangement such as shown schematically in Figure 3 may be used. In Figure 3, elements 22 through 29 are intended to represent in a general way the construction of a standard frequency modulation receiver of the type which is now commercially available for radio reception. In such a receiver energy picked up by antenna 22 is amplified in a radio frequency amplifier 23, converted into a suitable intermediate frequency in a converter-oscillator 24, amplified in a suitable intermediate amplifier 25, treated in a limiter 26 in order to remove any existing amplitude modulation, detected in a discriminator-detector

27, amplified in an audio-frequency amplifier 28 and fed to a loud speaker or other translator 29.

While it may be possible to record the intermediate frequency output of the limiter 26 directly by impressing the output voltage of 26 across the two plates 9 and 10 of a crystal recorder such as shown in Figure 1, it will be found that the frequencies involved are usually too high and the frequency swing too great for efficient recording and reproduction. Accordingly, the present invention provides a novel energy conditioning circuit which may be interposed between the limiter 26 and a suitable recorder 36 for reducing both frequency swing and mean frequency. A suitable conditioning circuit may comprise a combination of one or more converters, one or more frequency dividers and one or more frequency multipliers arranged in any suitable manner to provide any desired mean frequency and any desired frequency swing for efficient recording. One of many possible arrangements has been illustrated in Figure 3, wherein the output of limiter 26 is fed to a converter 31 through switch 33 (when closed) for frequency reducing purposes. Of course, while a converter such as 31 takes care of frequency reduction, it cannot reduce the frequency swing. To reduce the frequency swing, the energy from converter 31 is fed to a frequency divider 32. Frequency dividers capable of dividing by any desired divisor may in some cases be difficult to construct, so that in accordance with the present invention the effect of dividing by a suitable divisor is obtained through the use of a suitable combination of frequency dividers 32 and frequency multipliers 33. One or more additional converters may be desirable for frequency reduction in several steps in order to simplify the frequency swing reduction. In such a case one or more suitable converters such as 34 may be provided. It is obvious from a mathematical standpoint that substantially any desired frequency and frequency swing may be obtained by properly combining frequency conversion, frequency multiplication and frequency division.

After the energy is converted to the proper frequency and frequency swing, it may be fed to the recorder 36 through an amplifier 35 and recorded on a suitable record such as the disc 12 shown in Figure 1.

From the preceding matter, it can be seen at once that a record prepared in accordance with the present invention cannot be played back efficiently through a standard frequency modulation receiver by simply impressing the voltage picked up by a pickup, as for instance that shown at 17 in Figure 2, directly upon the input of the intermediate frequency amplifier of the receiver shown in Figure 3. The reason for this is that amplifier 25 is ordinarily designed for operation at much higher frequencies than are picked up from the record. Also, frequency modulation receivers are designed for greater frequency swings than those on the record. Accordingly, the output of the pickup 41 should not only be converted to higher frequencies but in addition its frequency swing should be increased. For this purpose the invention provides a circuit arrangement intermediate the output of pickup 41 and the input of intermediate amplifier 25 which conditions the energy picked up by pickup 41 for proper and efficient handling by the frequency modulation receiver. A suitable circuit for this purpose may comprise an amplifier 40 for amplifying the voltage picked up by 41, a frequency multiplier 39 for

increasing the frequency swing to the desired value and a converter 38 to convert the mean frequency to a value suited to amplifier 25. The output of the converter 38 is fed to the input of intermediate frequency amplifier 25 through a suitable switching means 37.

It may sometimes be desirable to produce a record of the type described herein with ordinary cutting equipment; that is, equipment which is designed for operation at the usual audio-frequencies. In such an event, the present invention provides a system of slow speed recording which may take the form shown schematically in Figures 4A and 4B. Since in slow speed recording everything must be slowed down proportionately in order that the record when played back at the usual speed will provide faithful reproduction, it is necessary to, so to speak, slow down the audio-frequency. One feasible method of doing this is to record the audio-frequency derived from a device 42 which may be a microphone, onto a record 12 in the usual manner, as indicated in Figure 4A. In other words, the audio-frequency output of 42 is amplified in a suitable audio-frequency amplifier 43 and the resulting voltage impressed between plates 9 and 10 of crystal 44. Crystal 44 is then used to drive a suitable cutter which cuts the record 12 in accordance with the audio-frequency voltage impressed between plates 9 and 10. As in Figure 1, the record 12 is placed on a turn table 13 with its hole registering with spindle 14 as is usual. The turn table 13 is rotated by means of motor 16 through reduction gearing 15 similar to the arrangement shown in Figure 1. The record 12 may then be placed on a reproducing turn table 50 (see Figure 4B) which may be similar to the turn table 13 of Figure 4A except that motor 51 drives turn table 50 through reduction gearing 52 and spindle 53 at a much lower speed than that at which the record was made.

A pickup 45 is used to pick up the signals from the record 12 and to feed them to a reactance tube circuit 46 similar to the reactance tube circuit 3 of Figure 1. The reactance tube circuit 46 is used to frequency modulate energy generated by oscillator 47, and this frequency modulated energy is converted in 48, then amplified in 49, and applied to recorder 54. It is to be understood, however, that the mean frequency of the waves applied to 54 is reduced from the value to be yielded by the record in normal use in the same proportion as the speed of turn table 50 is reduced.

In playing back a record made by the recording mechanism 54 it should be run at its normal speed. In other words, such a record may be played back by either of the systems shown in Figures 2 and 3 without altering the record driving mechanisms thereof.

Comparing the arrangement shown in Figure 4B with the arrangement shown in Figure 1, it should be noted that assuming that the turn table 50 of Figure 4B is operating at $1/10$ th the speed at which the record is to be played back in a system such as shown in either Figures 2 or 3, then the mean frequency of waves impressed on 54 is $1/10$ th of the frequency of the waves impressed on tool 11 of Figure 1. Likewise, the turn table associated with recording mechanism 54 operates at $1/10$ th the speed of turn table 13 shown in Figure 1.

In the foregoing description, for the sake of definiteness, a disc recording system was described for the recording and playing back at

reduced speed of the signals originating at microphone 42. However, inasmuch as any imperfection which may occur during this intermediate stage of recording and reproducing in the conventional fashion will be evident in the final frequency modulated record, it would be preferable to use for this intermediate handling of the signals a photographic film type of record arranged to operate at a sufficiently high linear speed so as to produce the highest possible fidelity and lowest possible background noise.

At this point one might well inquire whether there is any reason for producing a frequency modulated record at all if, in the process of making this record, a substantially perfect record of the ordinary type has to be made. That is, if a substantially perfect record can be made, why should not it or a copy thereof be played back in the conventional manner by the ultimate user of the record?

The answer to this question is that while substantially perfect recording and reproduction may be possible in the laboratory and in connection with the system as above described, the bulk of such a record and the great expense of the equipment for playing it back with high fidelity is such as to make it impractical for use by the ordinary user. Such equipment, however, is justified as a step in a manufacturing process for producing a large number of copies of the ultimate frequency modulated product adapted for use by the ordinary user.

Another type of recording which may be used is illustrated in Figure 7 wherein the record 12, or at least the "land" thereof, is composed of a light reflecting material. In order to reproduce from such a record, a source of light 60 is arranged so that the light therefrom passes through an optical system including lens 61 and as indicated at 65, is reflected to a photo-electric cell 64 from one particular "land" which may thus be selected by an opening 62 of reasonable size in arm 63. The size of the opening is such that a photo-electric cell 64 receives the light reflected from one point on the "land." In other words, at each wave of the record undulations a single pulse is delivered by the pick-up. In the arrangement illustrated, the arm 63 also acts as the guiding means for the source of light, it being noted that the end thereof cooperates with the record groove to feed the source of light and photocell across the record. The output of the photocell may be impressed upon the input of a suitable amplifier such as amplifier 48 shown in Figure 2 or amplifier 40 shown in Figure 3 of the drawings, and the signals are derived therefrom in the manner set forth in either of said Figures 2 and 3.

A preferred type of cutting or embossing tool is shown in Figure 5 wherein there is illustrated a section of a record 12 (greatly enlarged) in the process of being cut or embossed by means of tool 11 which is being driven by crystal 8. While the tool 11 is shown as having a rounded point, it should be understood that it may be shaped for either cutting or embossing depending upon the type of recording preferred. Any suitable arrangement for holding the tool 11 in place may be used. One such arrangement may comprise a set screw 55 which acts to hold the tool 11 tightly in its receptacle. The portion 56 of the "land" is the part which has been embossed or cut while portion 57 shows the uncut portion.

In Figure 6, a pickup 11 is shown being guided along the "land" of the record 12 by means of a

grooved follower 58 the point 59 of which is adapted to fit into the record groove. Follower 58 may be attached to the crystal carrier 71 in any suitable manner as by means of a suitable resilient mounting means 70.

It is to be understood that a variable resistance or capacity type pickup arrangement may be used if desired. In one such arrangement the "land" of a hill and dale (preferably conductive) record may be used as one plate of a condenser in which case a suitable condenser electrode which is guided just above the "land" by a guiding means working in conjunction with the groove as shown in Figures 6 and 7 forms the other condenser plate. The varying distance between the guided plate and the "land" provides a variable capacity which may be connected in series with a source of current and an impedance element to form a series circuit. Potential variations across the impedance element may then be impressed upon the input of an amplifier circuit such as shown at 48 in Figure 2. The amplified energy may then be fed to a discriminator detector as in Figure 2 in order to derive the signals, and after amplification the signals may be fed to a loud speaker or other suitable utilizing device.

It will be evident that a most important advantage of the system of recording and reproducing herein disclosed is that it offers a practical method of editing recorded subject matter without introducing distortion. It is sometimes desirable to record an entire program in order to assure obtaining all the various desired portions of the program. While editing is possible with present day recording systems, it is evident that distortion is introduced in playing back the subject matter and in re-recording the desired portions thereof due to the difficulty of following a complex waveform with both the reproducing pickup and the recording tool. With a frequency modulated wave recording of the type disclosed herein such distortion is avoided because the signal energy is resolved into purely frequency changes of a carrier so that the recorded frequency modulated wave may be derived from the original record and recorded directly on another record without the necessity of deriving the audio-frequency signals therefrom.

While there have been indicated and described several systems for carrying the present invention into effect, it will be apparent to one skilled in the art that the invention is by no means limited to the particular organization shown and described but that many modifications may be made without departing from the scope of the invention as set forth in the appended claims.

I claim:

1. The method of recording audible signals which comprises the steps of producing alternating electric energy of substantially constant amplitude and having a mean frequency of the order of 50,000 cycles per second; frequency modulating said energy as a function of said signals; recording the resultant frequency modulated energy on a recording medium; and maintaining the ratio of maximum frequency to minimum frequency of said frequency modulated energy, small as compared to the ratio of maximum frequency to minimum frequency of said signals.

2. The method of recording audio-frequency electrical energy of variable intensity and frequency, which comprises the steps of producing alternating electrical waves of super-audible

frequency varying the frequency of said waves above and below a mean value in accordance with the intensity of the audio-frequency energy and at a rate which is dependent upon the frequency of the audio-frequency energy; and recording the resultant waves on a recording medium, the ratio of maximum frequency to minimum frequency of the frequency modulated waves being a fraction of the ratio of maximum frequency to minimum frequency of the audio-frequency energy, and the difference between the maximum frequency and the minimum frequency of the frequency modulated waves being a multiple of the difference between the maximum frequency and the minimum frequency of the audio-frequency energy.

3. The method of recording audio-frequency signals of variable intensity and frequency which comprises the steps of: recording the audio signals at a predetermined speed; producing electrical waves of super-audible frequency; transforming said recorded audio signals into electrical signals of lower audio frequencies by reproducing said recording at a substantially lower speed than said recording speed; varying the frequency of said super-audible frequency waves above and below a mean value in accordance with the intensity and the frequencies of the last-named audio-frequency signals; and recording the resultant frequency modulated waves on a recording medium.

4. In a sound recording method, the steps of: producing audio-frequency electrical energy representing the sound desired to be recorded and later recreated; generating alternating electrical waves of super-audible frequency; frequency modulating said super-audible waves over a wide frequency range in accordance with said audio-frequency energy, reducing the frequency of the frequency modulated waves, transforming the reduced frequency waves into corresponding mechanical vibrations and imparting to a solid recording medium shape undulations corresponding to said vibrations.

5. In a combination radio signal receiving and record transducing apparatus for receiving and utilizing timing modulated carrier waves: a circuit including a converter network to reduce received waves to an intermediate frequency range an amplitude modulation limiter network following the converter; a detection network following the limiter network; and utilizing means coupled to the limiter; said utilizing means including signal recording structure for recording timing modulated waves of lower mean frequency and lower frequency swing; a conditioning circuit coupled to the limiter network for reducing both the frequency swing and mean frequency of the modulated wave output of the limiter to that of the recording structure; and connecting means for supplying the conditioned modulated wave energy to the recording structure.

6. In a combination radio signal receiving and record transducing apparatus for receiving and utilizing timing modulated carrier waves and having a circuit including a converter network to reduce received waves to an intermediate frequency range an amplitude modulation limiter network following the converter; a detection network following the limiter network; and a modulation voltage utilizing network coupled to the detection network; the improvement which is characterized by a reproducing network for utilizing said receiver to reproduce records of

frequency modulated super-audible waves having a mean frequency and frequency swing different from said intermediate frequency range, said reproducer network comprising transducing means for converting the records into said super-audible waves; a conditioning circuit coupling said transducing means to a point of the receiver between said converter and limiter, said conditioning circuit being constructed to conform the frequency swing and mean frequency of the modulated super-audible waves to those of said intermediate frequency receiver.

7. The method of reproducing signals which comprises the steps of producing a first recording of the signals at a predetermined recording speed; playing back the produced recording at a speed which is lower than the speed at which it was recorded; using the slow speed play back signals to frequency modulate a carrier frequency wave; recording the resultant frequency modulated energy upon a recording medium operating at a speed which corresponds to the said slow speed play back; playing back the last named recording at a speed corresponding to the recording speed of the first named recording; and deriving the desired signals from the last named play back.

8. In a frequency modulation receiver of the superheterodyne type including an intermediate frequency network, an amplitude limiter and a discriminator-detector network; the improvement which comprises a record pickup, means for translating the current output of the pickup into frequency modulated wave energy having a mean frequency equal to the operating intermediate frequency of said receiver, and means for selectively connecting the output of the translating means to said intermediate frequency network.

9. In a frequency modulation receiver of the superheterodyne type including an intermediate frequency network and a discriminator-detector network; the improvement which comprises a record pickup, means for translating the current output of the pickup into frequency modulated wave energy having a mean frequency equal to the operating intermediate frequency of said receiver, and means for connecting the output of the translating means to said intermediate frequency network.

10. A method of recording signals as defined by claim 1 in which the recording is made by imparting to a solid recording medium variations in shape corresponding to the energy alternations.

11. In a recording apparatus for recording audible signals as a series of undulations on a record member from which the signals may be reproduced by interaction of the undulations with undulation-following means without appreciable interference from extraneous noise: electric wave supply structure for supplying electric waves having a substantially constant amplitude and a frequency of the order of 50,000 cycles per second; said supply structure including modulating means having an input circuit for connection to a source of said audible signals and having an output circuit connected in said structure to vary the frequencies of the waves supplied by the structure, in accordance with variations in amplitude and frequency of said audible signals for providing substantially constant amplitude, frequency modulated waves having a frequency swing larger than the frequency range of said audible signals; and recording structure connected to said supply

13.

structure for imparting to a solid record member undulatory changes in shape corresponding to the frequency modulated waves.

12. The combination as defined by claim 11 in which the modulating structure is connected for varying the wave frequency over a frequency range which is a multiple of the frequency range of the audible signals.

13. The combination as defined by claim 11 in which the recording structure includes a record deforming element held for vibration in accordance with the frequency modulated waves in a direction producing record undulations of varying depth in the record.

14. In a recording apparatus for recording audible signals as a series of signal modulated undulations on a record member from which the signals may be reproduced by demodulation from waves generated through interaction of the undulations with undulation-following means, without appreciable interference from extraneous noise: record signal supply structure for supplying readily recordable low frequency electric waves, frequency modulated in accordance with said audible signals; said record signal supply structure including signal input means connected for delivering waves having frequencies higher than said readily recordable waves, and frequency reducing means connected to said input means to uniformly reduce the frequencies of said frequency modulated waves to said readily recordable frequencies; and recording structure connected to said supply structure for imparting to a solid record member undulatory changes in shape corresponding to the modulated waves of reduced frequency.

15. A recording apparatus as defined by claim 14 in which the frequency reducing means includes converter elements for uniformly reducing the wave frequencies by a substantially constant frequency.

16. A recording apparatus as defined by claim 14 in which the frequency reducing means includes frequency divider structure for reducing the wave frequencies by a substantially uniform fraction of their frequencies.

17. A recording apparatus as defined by claim 14 in which the frequency reducing means includes intermediate record transducing elements connected for making an intermediate record of the audible signals and deriving from the intermediate record, low frequency signals corresponding to said audible signals but with frequencies uniformly reduced to a fraction of the original frequencies of said audible signals; and the record signal supply structure also includes generator means for supplying carrier waves correspondingly lower in frequency than the frequency of the carrier to be reproduced from said record member, and modulating means connected for frequency modulating said carrier waves in accordance with said low frequency signals to provide modulated signals for transfer to the recording structure to make a final recording at a final recording speed lower than a predetermined reproducing speed, from which final recording the desired audible signals can be reproduced.

18. In an apparatus for recording signals as super-audible, frequency modulated undulations in a record medium: first recording means including a recording head and record advancing means for preparing a record of said signals at a predetermined speed of record advance with respect to the recording head; playback means including a playback head and record advancing

14.

means connected for transducing said record to play back signals while the record is advanced with respect to the playback head at a speed lower than the speed of said recording; and second recording means connected for receiving said playback signals and preparing a frequency modulated recording of the last-mentioned signals as physical undulations in a recording medium; said second recording means including supply structure connected to supply for said frequency modulated recording, a carrier wave having a frequency such that when multiplied by the ratio of said first recording speed to said playback speed it is above the audible range.

19. In an apparatus for recording signals as super-audible, frequency modulated undulations in a record medium: first recording means including a recording head and record advancing means for preparing a record of said signals at a predetermined speed of record advance with respect to the recording head; playback means including a playback head and record advancing means connected for transducing said record to play back signals while the record is advanced with respect to the playback head at a speed lower than the speed of said recording; and second recording means connected for receiving said playback signals and preparing a frequency modulated recording of said last-mentioned signals as physical undulations in a recording medium; said second recording means including supply structure connected to supply for said frequency modulated recording, a carrier wave having a frequency such that when multiplied by the ratio of said first recording speed to said playback speed it is of the order of 50,000 cycles per second.

20. In a signal transducing apparatus having a pass circuit including an input network for receiving frequency modulated waves, an intermediate frequency network connected to said input network for amplifying received waves having predetermined values of mean frequency and frequency swing, and an output network including modulation deriving means connected to the intermediate frequency network for delivering amplified signals corresponding to the modulations of said amplified waves record transducing means connected for transducing frequency modulated records of record signals having predetermined values of mean frequency and frequency swing different from said first-mentioned predetermined values; said transducing means including a record transducing circuit having circuit elements connected for including at least a part of said intermediate frequency network in said record transducing circuit for amplifying said record signals; said transducing circuit including a conditioning network connected for changing the mean frequency and frequency swing of signals in said transducing circuit from one of said predetermined values to the other for transducing records without separately deriving the record signal modulations.

21. The combination as defined by claim 20 in which the transducing means includes recording elements connected for making records of the record signals, and the transducing circuit is connected to receive the record signals from the intermediate frequency network of the pass circuit.

22. The combination as defined by claim 20 in which the transducing means includes record reproducing elements for reproducing the record signals from recordings and the transducing circuit is connected to deliver the record signals to

15

the intermediate frequency network of the pass circuit.
